(57) **CLAIM**

The ornamental design for a tissue dispenser with photograph display, as shown and described.

DESCRIPTION

FIG. 1 is an isometric view of tissue dispenser with photograph display showing my new design with the lid removed; FIG. 2 is an isometric view of the dispenser with the lid applied and a portion cut away;

FIG. 3 is a top plan view thereof with the lid removed; FIG. 4 is a front elevation view thereof with the lid applied, the rear elevation, left side elevation, and right side elevation being identical;

FIG. 5 is a cross sectional view thereof taken from line 5-5 in FIG. 7;

FIG. 6 is a cross sectional view thereof showing the lid separated, taken from line 6-6 in FIG. 7;

FIG. 7 is a top plan view thereof with the lid applied; and, FIG. 8 is a bottom plan view thereof.

The broken line showing of parts of the drawings is included for the purpose of illustrating use and environment and forms no part of the claimed design.

The primary criteria for the design was to create the optimum viewing of photographs on all four sides and to allow the dispensing of facial tissues. Further, the design was intended to replace both the tissue box and the many photograph frames from the furniture where photographs are normally displayed, and tissues are dispensed.

1 Claim, 8 Drawing Sheets
